(57) **CLAIM**

The ornamental design for a tongue cleaner for a baby, as shown and described.

DESCRIPTION

FIG. 1 is a front perspective view of a tongue cleaner for a baby showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dashed broken lines in the figures show portions of the tongue cleaner that form no part of the claimed design. The shade lines in the figures shown contour and not surface ornamentation.

1 Claim, 7 Drawing Sheets
